UNITED STATES PATENT OFFICE.

HENRY E. HUBBARD, OF OAK PARK, ILLINOIS, ASSIGNOR TO ADDRESSOGRAPH COMPANY, OF CHICAGO, ILLINOIS, A CORPORATION OF ILLINOIS.

SECTIONAL PRINTING-FORM.

1,209,412.

Specification of Letters Patent. Patented Dec. 19, 1916.

Application filed October 13, 1913. Serial No. 794,799.

To all whom it may concern:

Be it known that I, HENRY E. HUBBARD, a citizen of the United States, residing at Oak Park, in the county of Cook and State of Illinois, have invented certain new and useful Improvements in Sectional Printing-Forms, of which the following is a specification.

This invention relates to printing forms in general and more particularly to a sectional printing form adapted to print a full page letter or circular at one impression.

One of the primary objects of the present invention is the provision of a sectional printing form which shall be made up of a plurality of sheet metal form sections locked upon a bed in which the means holding them in place are so arranged that they will not contact with the ribbon or other inking mechanism and subsequently contact with the sheets being printed and smudge the same.

Another object of the invention is to provide printing form sections for use in sectional printing forms which will be strong and durable in operation and which may be cheaply constructed.

Other objects and advantages of the invention will be apparent as it is better understood by reference to the following description when considered in connection with the accompanying drawing, illustrating a preferred embodiment thereof.

Referring to the drawing, Figure 1 is a transverse sectional view through a flat sectional printing form embodying my invention; Fig. 2 is a similar view of a sectional printing form curved longitudinally of the form sections; Fig. 3 is a similar view through a sectional printing form curved transversely of the form sections; Fig. 4 is a partial plan view of the sectional printing form shown in Fig. 3, and Fig. 5 is a perspective view of one of the form sections.

On the drawing, and referring more particularly to Fig. 1, the sectional printing form embodying my invention comprises a bed 11, having a plurality of spaced grooves therein and a plurality of printing form sections 12 arranged thereon and secured in position by fastening devices 13 and 14. The devices 13 and 14 preferably consist of strips of metal, shaped as hereinafter described, to engage the ends of the form sections, each strip extending preferably, although not

necessarily, along the length of the bed. The bed is cut away at each side at 15 to provide recesses in which the strips are secured, the thickness of the strips being preferably substantially equal to the depth of the recesses 15. One of the strips, in the present instance 13, is preferably permanently secured to the bed by screws or similar fastening means 16 and this strip is cut away on its under face adjacent the inner wall of the recess to provide a groove 17 between the strip and the bed in which the end of the printing sections are engaged. Both ends of each printing form section are bent at 18 at an angle with the body of the printing form to provide an inclined portion 19 and are bent again at 20 to provide a lip 21 disposed in a plane parallel to the body portion of the section. The lip 21 at one end of the form section is adapted to be inserted, when the section is to be positioned on the bed, in the groove 17.

The printing form sections 12 are provided with depending flanges 9 to engage the grooves 10 in the bed 11.

The other strip 14 is preferably detachable and is held in place by screws 22 which may be readily removed. Like the strip 13 this strip is cut away on its lower side to provide a groove 23 in which the other lips 21 of the form sections may be engaged. The groove 23, however, extends almost across the under face of the strip leaving at the outer edge a rib 24 adapted to rest upon the face of the recess 15, which is parallel with the face of the main portion of the bed. The screws 22 are positioned inwardly of this rib and the parts are so diminished that only the inner edge of the strip 14 rests upon the lips 21 of the form sections when the strip is positioned. The screwing down, therefore, of the screws 22 will firmly and yieldingly hold the strip and the form sections in place.

Figs. 2, 3 and 4 show the application of the same fastening means to curved sectional printing forms, the recesses 25 (Fig. 2) being formed by providing channels in the surface of the bed 26 in which the strips 27 and 28, similar to the strips 13 and 14, are secured by screws 29. When the form sections are disposed axially of a curved bed as shown in Figs. 3 and 4, the fastening means are secured to the circumferential edges of the bed in recesses similar to those

shown in Fig. 1. The bed 32 in these figures is cylindrical in shape and a number of segmental strip sections 31 abutting at their ends at 33 and together forming a band 5 are preferably provided about each end of the bed.

The form sections secured in place upon the curved beds shown in Figs. 2 and 3 are substantially identical with the ones shown 10 in Fig. 5, except that they are curved throughout their length in the form shown in Fig. 2 and curved transversely in the form shown in Fig. 3 to conform to the shape of the bed.

15 As the upper surfaces of the fastening strips in each embodiment are disposed substantially flush with the outer surface of the bed, these surfaces of the strips must lie beneath the outer surfaces of the printing 20 forms upon which the printing characters 34 are provided and when so placed it will be apparent that they will not contact with the inking mechanism and receive ink which later may be transferred to the paper being 25 printed to dirty or smudge the latter.

It will be apparent also that the provision of the incline portion 19 to connect the lips 21 with the body of the printing form sections will reduce materially any weakening 30 effect that the off-setting of these lips from the plane of the body portion might have and these portions also permit the printing form sections to be positioned and locked in place much more readily than would be 35 the case were the lips connected with the

body portion by portions disposed at right angles to the two.

It will be obvious that various changes may be made in the form and construction of the parts and their arrangements without departing from the spirit and scope of our invention, or sacrificing any of its benefits, the forms hereinbefore described being merely preferred embodiments thereof. 40

I claim:

A sectional printing form comprising a bed provided with a plurality of spaced grooves, a plurality of printing form sections consisting of thin metal plates having printing characters struck up from the body 50 thereof, said sections being provided with depending flanges along the longitudinal edges thereof and being arranged side by side on said bed in abutting relation with said flanges disposed in said grooves, depressions in said bed transversely of said sections, the ends of said sections being inclined downwardly and bent outwardly in substantial parallelism with said bed, fastening strips in said grooves provided with 55 rabbeted edges overlying the ends of a plurality of said sections, and means for securing said strips to said bed with the upper surfaces thereof below the plane of the printing surfaces of said sections. 60
